UNITED STATES PATENT OFFICE.

HENRY W. FISHEL, OF NEW YORK, N. Y.

DESIGN FOR AN ARTICLE OF JEWELRY.

58,309.

Specification for Design.

Patented July 12, 1921.

Application filed October 16, 1919. Serial No. 331,181. Term of patent 7 years.

To all whom it may concern:

Be it known that I, HENRY W. FISHEL, a citizen of the United States, residing at the borough of Manhattan, city, county, and State of New York, have invented a new, original, and ornamental Design for Articles of Jewelry, of which the following is a specification, reference being had to the accompanying drawings, forming part thereof.

Fig. 2 is an edge view thereof.

I claim:

The ornamental design for an article of jewelry as shown.

In testimony whereof, I have affixed my signature to this specification.

HENRY W. FISHEL.
